(57) CLAIM

I claim the ornamental design for a ring, as shown and described.

DESCRIPTION

FIG. 1 is a perspective view of a ring, showing my new design;

FIG. 2 is a front elevational view thereof;

FIG. 3 is a left-side elevational view thereof;

FIG. 4 is a top plan view thereof; and,

FIG. 5 is a bottom plan view thereof.

The text that spells the word “TeamO” in the drawings and forming part of the claimed design is a trademark of Teamo, LLC, of Edmond, Okla.

The broken lines showing a team logo in FIGS. 1 and 4 depict environmental matter and form no part of the claimed design.
